UNITED STATES PATENT OFFICE.

ERIC R. LUNDIUS, OF BROOKLYN, NEW YORK, ASSIGNOR TO WESTERN ELECTRIC COMPANY, INCORPORATED, OF NEW YORK, N. Y., A CORPORATION OF NEW YORK.

TELEPHONE SYSTEM.

1,281,611.

Specification of Letters Patent. Patented Oct. 15, 1918.

Application filed December 26, 1917. Serial No. 208,830.

To all whom it may concern:

Be it known that I, ERIC R. LUNDIUS, a citizen of the United States, residing at Brooklyn, in the county of Kings, State of New York, have invented certain new and useful Improvements in Telephone Systems, of which the following is a full, clear, concise, and exact description.

This invention relates to telephone systems and more particularly to such systems employing a ring-up relay responsive to ringing current for controlling signaling devices.

The principal object of this invention is to provide an improved signaling means for said systems.

In telephone systems employing a ring-up relay in series with a condenser and responsive to ringing current for controlling a signaling device, considerable difficulty has been experienced, due to the false operation of this relay when the answering operator or the originating subscriber or operator disconnects. In the system embodying the present invention, this difficulty is overcome by providing a discharge path for the condenser when the operator responds to the call.

This invention will be more fully understood from a consideration of the following description in connection with the accompanying drawing, illustrating one embodiment thereof.

As shown in the drawing, the trunk circuit B extends from an originating operator's position X to a terminating operator's position Y. At the position X there is provided a cord circuit A, adapted for connection with the outgoing terminal of the trunk circuit B, while at the position Y is located line signal controlled apparatus and switching apparatus for connecting the answering operator's telephone set with the trunk circuit B.

The originating operator in establishing a connection with the trunk circuit, inserts plug 5 in jack 6 and actuates ringing key 7, thus connecting a source of current 8 therewith. The ring-up relay 9 is thereupon operated over a circuit from a source of current 8 through the lower contact of ringing key 7, ring contacts of the plug 5 and jack 6, left-hand normal contact of cut-off relay 13, condenser 10, left-hand winding

of the ring-up relay 9, tip contact of the 55 jack 6 and plug 5, and upper contact of ringing key 7 to ground. Relay 9 in operating causes the intermittent lighting of line lamp 11 over a circuit from battery, through line lamp 11, right-hand contact of relay 9 and 60 interrupter 12 to ground. Relay 9 in operating also establishes a locking circuit for itself through its right-hand winding and left-hand contact, and right-hand normal contact of cut-off relay 13 to ground. The 65 operator at Y, upon observing the intermittent glow of line lamp 11, actuates listening key 14 which, through its upper and middle contacts, connects an operator's telephone set (not shown) across the trunk circuit. 70 Cut-off relay 13 upon the actuation of the listening key 14 is energized over a circuit from battery through the winding of cut-off relay 13 and the lower contact of listening key 14 to ground.

Cut-off relay 13, in operating, opens its normal and closes its alternate contacts. The opening of the left-hand normal contact disconnects the bridge from the talking circuit, which includes the line winding of 80 relay 9 and condenser 10. In closing its left-hand alternate contact, the condenser 10 is thereupon included in a closed circuit with the line winding of relay 9, thus establishing a discharge path for the condenser. 85 The opening of the right-hand normal contact of the cut-off relay 13, opens the locking circuit of relay 9, thus causing its release, which in turn excludes the interrupter 12 from the line lamp circuit. The closing 90 of its right-hand alternate contact causes the continuous illumination of line lamp 11 over a circuit from grounded battery through line lamp 11 and left-hand alternate contact of cut-off relay 13 to ground. 95

In systems heretofore employed in which the energizing winding of the ring-up relay and the condenser remain connected with the line after the terminating operator answers, the condenser is then charged. When the operator disconnects from the line, there is a surge of current over the line due to the interruption of the circuit and since the condenser is already charged, very frequently causes the discharge thereof, resulting in the energization and locking up of the ring-up relay which causes a false signal. By having the condenser in a discharged

condition when reconnected with the line upon the disconnection of the operator, eliminates the possibility of this false operation of the ring-up relay and the line signal.

5 The terminating or answering operator in releasing the listening key 14 causes the de-energization of cut-off relay 13 and the subsequent release of its armatures, which in turn connect the condenser 10 in series with 10 the line winding of relay 9. The false operation of relay 9 is thus prevented by the insertion of condenser 10 in series with the line winding of relay 9.

What is claimed is:

15 1. A telephone system comprising a telephone line terminating at a switchboard, a relay and a condenser connected in series, in bridge of the telephone line, a signaling device operated by the relay in response to

20 signaling current impressed on the line, an operator controlled switch, and means responsive to the actuation of the switch to establish a closed circuit including the condenser for causing the discharge thereof.

25 2. A telephone system comprising a telephone line terminating at a switchboard, a relay and a condenser connected in series, in bridge of the telephone line, a signaling device operated by the relay in response to 30 signaling current impressed on the line, an operator controlled switch, and an electro-magnetic switch responsive to the actuation of the switch to establish a closed circuit including the condenser for causing the dis- 35 charge thereof.

3. A telephone system comprising a telephone line terminating at a switchboard, a relay and a condenser connected in series, in bridge of the telephone line, a signaling 40 device operated by the relay in response to the signaling current impressed on the line, an operator's telephone set, means for connecting the telephone set to said telephone line, and means controlled by said connecting 45 means to establish a closed circuit in-

cluding the condenser for causing the discharge thereof.

4. A telephone system comprising a telephone line terminating at a switchboard, a relay and a condenser connected in series, 50 in bridge of the telephone line, a signaling device operated by the relay in response to signaling current impressed upon the line, an operator's telephone set, a manually operated key for connecting the telephone set 55 to said telephone line, and a relay controlled from the contacts of said key to establish a circuit including the condenser for causing the discharge thereof.

5. A telephone system comprising a telephone line terminating at a switchboard, a relay and a condenser connected in series, 60 in bridge of the telephone line, a signaling device operated by the relay in response to signaling current impressed on the line, an operator controlled switch, and means responsive to the actuation of the switch to 65 remove the bridge from the telephone line and simultaneously to connect the condenser in a closed circuit with the line winding of the relay, thereby causing the discharge of 70 the condenser.

6. A telephone system comprising a telephone line terminating at a switchboard, a relay and a condenser connected in series, 75 in bridge of the telephone line, a signaling device operated by the relay in response to signaling current impressed on the line, an operator controlled switch, and an electro-magnetic relay responsive to the actuation 80 of the switch to remove the bridge from the telephone line and simultaneously to connect the condenser in a closed circuit with a winding of the first mentioned relay, thereby causing the discharge of the condenser. 85

In witness whereof I hereunto subscribe my name this 20th day of December A. D., 1917.

ERIC R. LUNDIUS.
